UNITED STATES PATENT OFFICE.

WILLIAM M. KECK, OF COALINGA, CALIFORNIA.

WELL-DRILLING APPARATUS.

1,179,010.

Specification of Letters Patent. Patented Apr. 11, 1916.

Application filed July 6, 1914. Serial No. 849,082.

To all whom it may concern:

Be it known that I, WILLIAM M. KECK, a citizen of the United States, residing at Coalinga, in the county of Fresno and 5 State of California, have invented certain new and useful Improvements in Well-Drilling Apparatus, of which the following is a specification.

This invention relates to well drilling apparatus and has particular reference to power wheels or drums for lifting and lowering tubing or the like, and the operating connections between the same and a source of power.

15 Heretofore the withdrawing or positioning of light weight tubing or casing within a well has been a slow and tedious operation owing to the slow operation of the calf wheel necessitated by the heavy material 20 which the same is required to handle and the constant speed of the power shaft.

The present invention has for one of its objects to provide a connection between the power shaft and the calf wheel, whereby 25 the rotation of the calf wheel may be changed without varying the speed of the power shaft, thereby providing a slow speed of rotation for the calf wheel when handling heavy loads and an accelerated rotation when it is desired to handle light loads.

Another object of the invention is to generally improve the construction of the calf wheel *per se*.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the appended claims may be resorted to without departing from the spirit or sacrificing any of the advantages of the invention.

To more fully comprehend the invention, reference is directed to the accompanying sheets of drawings, wherein—

Figure 1 is a substantially central horizontal section showing my improvements in a preferred embodiment. Fig. 2 is a vertical section on the line 2—2 of Fig. 1. Fig. 3 is a vertical section on the line 3—3 of Fig. 1. Fig. 4 is a detail of construction on the line 4—4 of Fig. 3, showing the manner of

connecting the high speed sprocket wheel to the calf wheel.

Referring more particularly to the several views of the drawings wherein like letters of reference designate corresponding parts throughout the several views, I show a supporting frame 10 providing bearings 11 and 12 for the gudgeons 13 and 14 respectively of the calf wheel construction.

A wheel head 15, in addition to the gudgeon 14, comprises a series of tangent spokes 16 shown as eight in number and secured at their outer ends to a rim 17. The drum portion 18 of the wheel is made preferably of a pair of concentric inner and outer tubes 19 and 20, the space between the walls of the tubes being filled with cement or some other suitable material adapted to become solid or hard after being set. The hub or gudgeon 14 is provided with a counterflange 22 which receives the adjacent end of the tube 20 and also is provided with a central annular lip or flange 23 which is inserted into the end of the inner tube 19, making a rigid end connection for the barrel or drum 18. A series of bolts 24 shown as four in number pass through the spokes, hub and drum structure, certain of the bolts being at right angles to the others, making a rigid structure. At the other end of the drum 18 the 85 gudgeon or hub 13 constitutes and carries a winch 25 which has characteristics similar to the other gudgeon with respect to the fastening means for the ends of the tubes 19 and 20. I employ, however, preferably 90 only two locking bolts 24' at this end of the drum.

I provide a pair of sprocket wheels 26 and 27 secured upon the head 15 and coaxial therewith. Surrounding the wheel 17 and 95 against which the sprocket wheel 26 bears is a metallic reinforcing or strengthening ring, which is of slightly smaller diameter than the sprocket wheel but acts to strengthen or retain this sprocket wheel in 100 position at all times. The sprocket wheel 26 is secured by means of bolts 28 direct to the rim 17. The sprocket wheel 27, however, is provided with a series of lugs 29 having faces applied squarely against the outer 105 faces of certain of the spokes 16, and through said lugs the smaller sprocket wheel is secured by means of bolts 30 to the spokes. As shown particularly in Fig. 1, the spokes are wider than the rim 17 and they are re- 110

cessed as shown at 16' on the side adjacent the wheel 27 so as to give a neat and substantial seat for the wheel 27 and to provide sufficient clearance for the sprocket 5 chain 27^a operating over said wheel. The sprocket chain 26^a operating over the larger wheel is spaced, therefore, laterally from the plane of the chain 27^a, the two sprocket wheels being arranged on opposite sides of 10 the head 15. The heads of the bolts 28 are preferably countersunk in the rims 17 to prevent any interference between the same and the chain 27^a.

At 31 I show a power wheel of any suitable construction and adapted to be operated from any suitable source of power at a substantially uniform speed. Said power wheel is secured to a power shaft 32 substantially parallel to the axis of the calf wheel and 20 mounted in bearings, one of which is shown at 33. A pair of sprocket wheels 34 are mounted loosely upon the end of the shaft 32 outside of the bearing 33. The inner or adjacent faces of said sprocket wheels 34 25 are preferably dished or concaved so as to provide a maximum space between them for the operation of a clutch sleeve 35 which is splined to the shaft. A yoke 36 co-operates with the clutch sleeve 35 and is provided 30 with a rock shaft 37 and lever 38 for manipulating the clutch so as to cause either of the wheels 34 to be operatively connected to the power shaft 32 while the other sprocket wheel 34 is permitted to run idly around the 35 shaft. The aforesaid sprocket chains 26^a and 27^a have constant engagement with the wheels 34 and the calf wheel sprocket wheels already stated. With the power shaft 32 operating at certain speed, if the drum 18' 40 be operated at a corresponding speed, the clutch 35 will be shifted so as to positively drive the wheel 27 from the chain 27^a in either direction. For slower work, as, for instance, during the manipulation of heavy 45 tubing or the like, the clutch will be shifted in the opposite direction, causing the control of the drum 18 to be had through the larger sprocket wheel 26 and its chain 26^a, and at a slower speed corresponding to the 50 difference in size between the two wheels 27 and 26.

Having thus described my invention, I claim as new and desire to secure by Letters Patent:—

55 1. In a device of the class described, the same comprising a pair of hollow hubs, means to support the hubs in alinement with each other, a drum connecting the hubs, the said drum comprising a pair of 60 concentric tubes spaced from each other and co-operating with concentric flanges formed in the hubs, the space between the tube being filled with concrete, a controlling head at one end of the drum, said head comprising 65 a series of spokes arranged tangentially

to the adjacent hub, a series of bolts clamping the spokes to the hub, a rim surrounding and connected to the spokes, the spokes being wider than the rim and recessed to form a seat, a sprocket wheel secured to said 70 spokes in said seat on one side of the head, and a sprocket wheel of different size secured to the opposite side of the head.

2. A device of the class described, comprising a pair of axially alined hubs, a pair of concentric tubes forming a drum connecting said hubs, a filler within the space between said tubes, a wheel carried by one hub, means for locking said wheel to the hub, and a pair of different size sprocket 75 wheels secured to the opposite faces of the 80 said wheel for the purposes specified.

3. A device of the class described comprising a drum, a controlling head arranged at one end of the drum, said head comprising 85 series of spokes operatively connected to the drum and a rim surrounding and connected to the spokes, the spokes being wider than the rim and recessed to form a seat, a sprocket wheel secured to the spokes in said 90 seat upon one side of the head and a sprocket wheel secured to the rim surrounding the head for the purposes specified.

4. A device of the class described, comprising a pair of hubs arranged in axial alinement with each other, each of said 95 hubs having concentric flanges, a pair of concentric tubes extending from one flange to the other and supported thereby, means to positively lock each end of the tube to the 100 adjacent hub, a head for one of the hubs and comprising a pair of spokes secured to the hub by the aforesaid locking means, a rim secured to the spokes, a pair of sprocket 105 wheels of different sizes secured to the opposite faces of the said head, a pair of sprocket chains operating over said different sized sprocket wheels and power means to operate said sprocket chains at the same speed in alternation.

5. A device of the class described, comprising a drum, a controlling head at one end of the drum, said head comprising a series of spokes operatively connected to the drum and a rim surrounding and connected to the spokes, said spokes being wider than the rim and recessed to form a seat, a sprocket wheel secured to the spokes in said seat upon one side of the head, and a sprocket 115 wheel secured to the rim at the opposite side of the head, a pair of sprocket chains operating on said sprocket wheel, and power means to operate said sprocket chains at the same speed in alternation.

6. A device of the class described, comprising a pair of actually alined hubs, a pair of concentric tubes connecting said hubs, a filler within the space between said tubes, a calf wheel carried by one hub, means for locking said calf wheel to the hub, a pair of 120 125 130

different sized sprocket wheels secured to the opposite faces of the calf wheel, a pair of sprocket chains operating over said different sized sprocket wheels and power 5 means to operate the said sprocket chains in alternation.

7. In a device of the class described, comprising a drum, a controlling head arranged at one end of the drum, said head comprising 10 a series of spokes operatively connected to the drum and a rim surrounded and connected to the spokes, the spokes being wider than the rim and having attached thereto a sprocket wheel, a second sprocket wheel secured to the rim, a pair of sprocket chains operating on said sprocket wheels, and power means to operate said sprocket chains 15 at the same speed in alternation.

Copies of this patent may be obtained for five cents each, by addressing the "Commissioner of Patents, Washington, D. C."

8. In a device of the class described, comprising a drum, a controlling head arranged 20 at one end of the drum, said head comprising a series of spokes operatively connected to the drum and a rim surrounding and connected to the spokes, the said spokes being recessed to form a seat, a sprocket wheel secured to the spokes in said seat, and a sprocket wheel secured to the rim substantially as described.

In testimony whereof I have signed my name to this specification in the presence of 25 two subscribing witnesses.

WILLIAM M. KECK.
